MACHINE FOR SEWING FASTENER TAPE AND THE LIKE

Application filed April 15, 1931. Serial No. 530,170.

This invention relates specifically to a machine for sewing fastener elements, for example, eyes or eyelets, upon fastener tape or other strips of fabric, although the invention 5 may be embodied in machines for sewing other impenetrable objects upon fabric strips, garments or the like, or for sewing strips containing fastener elements or other impenetrable objects upon the edges of garments, and for like purposes.

The invention relates in general to a machine such as shown in my Patent No. 1,742,221 dated January 7, 1930, and relates especially to a machine in which the work, for 15 example the fastener tape, is drawn or fed through sewing mechanism by intermittently rotated feed rolls which grip the tape or the like between them.

One feature of my invention relates to the 20 sewing of so-called transverse or bar stitches over the fastener elements or the like. In the making of fastener tape, it is customary to provide a longitudinal line of stitching on the tape which is interrupted at each fastener element to form in continuation thereof lateral transverse or bar stitches which overlie some portions of each fastener element. Usually these bar stitches are arranged one 25 upon the other or at distances apart corresponding to the length of the normal longitudinal stitches and are formed by lateral swinging of the needle bar of the sewing machine simultaneously with its reciprocation.

One object of my present invention is to 30 provide in a sewing machine novel and improved means for causing these bar stitches to be spaced or spread out over the fastener element at distances less than the length of the normal longitudinal stitches so as to 35 avoid the formation of protuberances or unusual thickness in the tape and also to provide a more secure attachment of the fastener element to the tape. This feature is particularly advantageous in fastener tape 40 wherein the fastener elements are in the form of eyelets which admit of the bar stitches being applied at only a limited portion of their circumference which is in striking contrast to the ordinary type of fastener elements which usually include a hook or

eye engaging portion and a base portion having a pair of loops both of which may be traversed by bar stitches to provide a secure attachment of the fastener elements to the 55 tape.

To accomplish the spreading of the bar 60 stitches as above-described, my invention further contemplates an auxiliary feed mechanism for the tape to engage a fastener element and which shall move the tape intermittently in steps shorter than the feeding steps of the main feed mechanism while the transverse or bar stitches are being formed. In the usual sewing machine, the 65 feeding movement of the feed rollers above-described is interrupted during the formation of the transverse bar stitches, and accordingly my said auxiliary feed is intended to operate to form the transverse stitches 70 while the feed rollers are at rest.

A further object is to provide in such a 75 work feed mechanism, auxiliary feed mechanism which also temporarily shall move the work independently of and at a greater speed than the main work feed mechanism to cause a long longitudinal stitch to pass over a portion of a fastener element.

Another object is to provide novel and 80 improved work feed mechanism of the character described whereby the speed of movement of the work is automatically varied at different times so that stitches of different lengths can be produced in a continuous series at different points in the work, as may 85 be desired.

Other objects are to provide novel and 90 improved auxiliary feed mechanism for moving the tape during the formation of the bar stitches, said mechanism to be arranged at the work discharge side of the needle; to provide a machine of the character described which shall be reliable and durable, and at the same time relatively simple in construction and operation; and to obtain other advantages and results as will be brought out 95 by the following description.

Referring to the accompanying drawings in which corresponding and like parts are 100 designated throughout the several views by the same reference characters,

Figure 1 is a front elevation of a sewing machine embodying my invention.

Figure 2 is a rear elevation thereof.

Figure 3 is an elevation of the end thereof 5 on which is mounted the needle mechanism.

Figure 4 is an enlarged fragmentary elevation of the stop device and auxiliary feed mechanism illustrated in Figure 3, with portions broken away and shown in section.

10 Figure 5 is a plan view of the parts shown in Figure 4, showing one step in the sewing operation.

Figure 6 is a similar view showing the 15 step during which the transverse bar stitches are formed.

Figure 7 is a like view showing a succeeding step.

Figure 8 is a composite perspective view 20 of the auxiliary feed dog parts, and

20 Figure 9 is a schematic end elevation of the driving mechanism for the feed rollers.

For the purpose of illustrating the principles of my invention, I have shown it in connection with a known type of sewing machine which includes a base A, a standard B and a goose-neck C. The machine has the usual drive shaft D to be driven by a belt passing over a pulley E on the drive shaft. At the free end of the goose-neck C is 25 mounted a needle bar F which is reciprocated in the usual manner from the drive shaft D. The needle bar is also mounted in a bracket arm G to oscillate simultaneously with its reciprocation. For oscillating the 30 bracket G, I have shown a cam wheel H mounted on a counter-shaft I journaled in the standard B and driven through worm and worm wheel gearing K from the drive shaft D. The cam H has cam projections h 35 to engage a follower roller L carried by a lever M pivoted to the goose-neck C at N and connected by a link O to the bracket G. The roller L is held in engagement with the cam H by a tension spring P. The needle 40 bar F carries a needle Q which is threaded and cooperates with a bobbin in known manner. All of the above-described details of construction are old in the art, some thereof being shown by my Patent No. 1,742,221 45 dated January 7, 1930.

The work to be operated upon, for example, the fastener tape, is passed beneath the needle Q to provide in the work a line of stitching as the needle is actuated. In 55 the present instance the work is in the form of a fastener tape R of known construction including a plurality of thicknesses r of fabric in one of which is secured a row of eyelets S substantially equidistantly spaced 60 longitudinally of the strip. The purpose of my machine is to sew these eyelets upon the tape by a longitudinal line of stitches 1 which is interrupted at each of the eyelets and has in continuation thereof a plurality 65 of transverse bar stitches 2 overlying a por-

tion of each of the eyelets. The tape R is passed through a guide 3 secured to the bed A of the machine and which also serves as a presser foot, the guide directing the tape in proper relation to the needle Q as 70 clearly shown in Figures 1, 4 and 5.

For feeding the tape longitudinally past the needle Q I utilize a pair of feed rollers 4 and 5 one of which is mounted on a shaft 6 journaled in a fixed bracket 7 on the bed 75 of the machine and at the rear side of the needle, that is, at the side of the needle from which the work leaves. The other roller 4 is mounted on a spindle 8 journaled in a bearing block 9 vertically slidable in a bracket 10 secured to the bed of the machine. These rollers 4 and 5 grip the fastener tape or other work between them, and the roller 4 is yieldingly forced toward the roller 5 to cause a gripping pressure of the 80 rollers upon the tape, by a compression spring 11 interposed between the bearing block 9 and one end of a lever 12 which is pivotally mounted intermediate its ends at 13 on the bracket 10.

The rollers 4 and 5 are driven from the drive shaft D of the machine, and as shown, the shaft 8 of the roller 4 is connected by a universal coupling 14 to a shaft 15 journaled in a standard 16 on the base A of the machine. The coupling 14 permits movements of the spindle 8 with respect to the shaft 15. The shafts 15 and 6 are geared together by gears 17 and 18, the first of which is mounted on the shaft 15, and the 90 shaft 15 has another gear 19 which meshes with a drive gear 20 mounted on a shaft 21 journaled in the standard 16. A pinion 22 on the shaft 21 meshes with a pinion 23 on another shaft 24 upon which is also mounted a gear 25 which meshes with a pinion 26 on a stub-shaft 27 all journaled in a frame 100 160. The shaft 27 has mounted thereon a pinwheel 28 with which meshes a suitably shaped worm 29 carried by a shaft 30 journaled in a bearing frame 31 which is mounted on the drive shaft D to swing concentrically therewith as shown in Figures 6 and 7 of my Patent No. 1,742,221. The shaft 30 carries a beveled pinion 32 which 105 meshes with a second beveled pinion 33 on the drive shaft D. The bearing frame 31 has a lateral arm 34 which carries a follower roller 35 arranged in a cam race 36 in a wheel 37 mounted on the counter shaft I at the rear side of the machine.

110 With this construction the feed rollers 4 and 5 are driven through the worm and pin-wheel 29 and 28 so as to feed the tape with an intermittent or step by step motion, each step being equal to the length of the desired stitch, which, in cooperation with the sewing mechanism causes a longitudinal line of stitches to be formed in the 115 work as it is fed by the feed rollers. As 120 125 130

a fastener element or eyelet S approaches the path of descent of the needle, the cam race 36 and the follower roller 35 swing the bearing frame 31 to disengage the worm 29 from the pin-wheel 28 so as to stop the feed rollers 4 and 5. Thereupon, the cam H oscillates the needle bar to form the transverse bar stitches 2. To prevent overthrow of the feed rollers when the worm 29 is disconnected from the pin-wheel 28, the arm 34 has a stop pawl 38 which enters between two of the teeth of the pin-wheel. This drive mechanism and the operation thereof is generally illustrated and described in my above mentioned Patent No. 1,742,221, with the exception of the gears 20 and 22. The purpose of these gears is to permit changing of the speed of the feed rollers 4 and 5 by substituting gears 21 having different numbers of teeth.

The feed rollers 4 and 5 are of such diameter and they move at such a speed that they can move the tape a small distance, for example, one-sixty-fourth of an inch, greater than the distance between the fastener elements, to provide a slight latitude for adjustment of the tape about to be described. To ensure proper presentation of the eyelets to the needle so as to avoid the possibility of the needle striking an eyelet and thereby becoming broken, I utilize with the feed rollers 4 and 5 a stop device to interrupt movement of the tape, in combination with means for diminishing or relieving the gripping pressure of the feed rollers upon the tape while the stop device is holding the tape against movement by the feed rollers. This stop device is in principle described and claimed in my Patent No. 1,605,902 dated November 2, 1926, but my present form of stop device differs from the patented device in details of construction. The present stop device includes a stop foot 39 mounted on the end of a rod 40 vertically slidable in the end of the goose-neck C of the sewing machine which carries the needle bar F. This stop foot has a stop pin 41 adjustably mounted thereon by screws 42 passing through a slot 43. The diameter of the stop pin 41 is considerably less than the diameter of the eyelets S as clearly shown in Figure 4 of the drawings. The stop pin is normally influenced toward the tape by a compression spring 44 adjusted by a thumb screw 45, and slidable upon the rod 40 is a sleeve 46 which engages a collar 47 rigidly secured on the rod 40 to raise the stop pin from the tape. This raising of the stop pin is accomplished by engagement of one end of a link 48 with a lug 49 projecting from the sleeve 44, the other end of said link being pivotally connected to a crank 50 on the shaft 51 mounted under the bed B of the machine. Upon this shaft 51 is another crank 52 to which is connected by a link 53

a lever 54 pivotally mounted at one end upon the bed of the machine at 55. The lever 54 at the other end has a roller 56 held by a tension spring 58 in engagement with a cam 57 which is mounted on the shaft I. With this construction, the stop pin 41 is alternately raised and lowered from and into contact with the tape, and the movement of the stop pin is so related to the movement of the tape by the feed rollers 4 and 5 that the stop pin enters one eyelet upon each descent of the stop pin to the tape. The distances between the eyelets vary slightly due to inaccuracies in inserting the eyelets, and slight irregularities in the feed of the tape by the feed rollers also occur, so that the stop pin may enter different eyelets at different distances from the inner edges of the eyelets, but the feed rollers will always draw the tape so that the rear side of each eyelet will engage the stop pin. The parts are so related that when an eyelet is brought into engagement with the stop pin, the succeeding eyelet approaching the path of the needle will be brought into exactly the proper position with respect to the needle for the formation of the first stitch 60 which traverses the leading side of the eyelet (see Figure 5).

As the result of this action, should the space between the eyelet engaged by the stop pin and the eyelet approaching the needle, for example, be shorter than the normal distance, the stop pin will stop movement of the tape by the feed rollers 4 and 5, i. e., the stop pin will oppose the tendency of the rollers to pull the tape. Accordingly it will be impossible for the eyelet approaching the needle to move to a point in the path of the needle so as to cause breakage thereof. If the space between the eyelet engaged by the stop pin and the eyelet approaching the needle is longer than normal, the stop pin will not be engaged by the rear edge of the eyelet so soon and therefore will not hold back the tape, at least not for so long a period as when the space is too short. The same action takes place should the feed of the tape by the feed rollers become irregular, and therefore any lack of uniformity in the spacing of the eyelets or in the feeding of the tape is compensated or adjusted as each eyelet reaches the stop device. It will be observed that the stop device is at the rear side of the needle and engages the tape after the latter has been stitched, while in my above-mentioned Patent No. 1,605,902 the stop device is in front of the needle. The present construction is more satisfactory in that the tape is stronger after having been stitched and is more capable of withstanding tension between the stop device and the feed rollers.

Means is provided for reducing the gripping pressure of the feed rollers upon the

tape while the tape is held back by the stop device, with the rollers at the same time maintaining a sufficient grip upon the tape to keep the tape under tension. This means 5 is shown as including the lever 12, the end of which opposite the end engaged by the spring 11 is hingedly connected to the link 48 which raises the stop foot rod 40, and is claimed in my copending application Serial 10 No. 530,171 filed April 15, 1931.

When the stop foot 39 is in its upper position, the link 48 holds the lever 12 so as to cause a maximum pressure by the spring 11 upon the roller 4, and thereby create a maximum gripping pressure of the feed rollers 15 upon the tape. As the stop foot is permitted to descend by the cam 57 through the link 48, the lever 12 is permitted to swing about its pivot so as to reduce or relieve the compression of the spring 11 so that the gripping pressure of the rollers on the tape is relieved or reduced. The pressure exerted by the spring 11 can be adjusted by the nut and screw device 61, or by screw 75 in Figure 20 25 or by adjusting sleeves 46 in Figure 3. When the normal pressure is correct, the reduced pressure may be adjusted by the screw 75 and sleeve 46; adjustment by screw 61 changes both pressures.

30 When each fastener element has approached a point with respect to the needle Q preparatory to making the first stitch 60 which traverses the fastener element, an auxiliary feed device disposed at the work 35 discharge side of the needle is brought into operation to engage an eyelet already stitched and move the tape independently of the feed rollers 4 and 5 which have been temporarily stopped by disengagement of 40 the worm 29 from the pin-wheel 28. This auxiliary feed device includes a dog 64 pivotally mounted at 65 on a slide bar 66 and having a tooth 67 to enter each eyelet S. This dog 64 is normally influenced toward 45 the tape by a leaf spring 68 and has a curved surface 69 receding from the tooth to ride backwardly over the tape.

The slide bar 66 is reciprocated by a lever 50 pivotally mounted intermediate its ends 70 at 71 on the bed of the machine and having a pin and slot connection 72 with the slide bar. The other end of the lever 70 carries a roller 73 which follows a cam 74 mounted on the shaft I. The roller is held in engagement with the cam by a spring 74. This cam has a cam surface 75 which swings the lever 70 to move the feed dog toward the needle, and another cam surface 76 to move the feed dog in the opposite direction. 55 These cam surfaces are so related to the movement of the tape and the stop device, that while the stop pin is disengaged from the tape, the dog 64 is moved toward the needle so as to drop under the influence of 60 the spring 68 into the eyelet next preceding 65

that leaving the stop device, as clearly shown in Figures 4 and 5 of the drawings.

The cam surface 76 then starts the feed dog away from the needle so as to permit the needle to form the stitch 60 which traverses the leading edge of the fastener element. The cam H then begins to oscillate the needle bar to form the transverse bar stitches 2, and simultaneously a plurality of stepped cam surfaces 77 on the cam 74 75 engage the roller 73 so as to continue movement of the feed dog with a step-by-step movement and thereby cause the transverse bar stitches to be spaced apart as clearly shown in Figure 6.

As the rear edge of the fastener element approaches the path of the needle, the oscillation of the needle bar is stopped, and the dog is moved to accelerate movement of the tape so that a long stitch 100 is made to 80 traverse the fastener element. Thereupon, movement of the feed rollers 4 and 5 is resumed, and the longitudinal line of stitches between the eyelet just stitched and the next succeeding eyelet is produced. At this time 85 the cam surface 75 returns the feed dog 64 to its starting position. It will thus be observed that the bar stitches 2 are arranged side by side so as not to form an undesirable protuberance on the tape, and that the bar 90 stitches cover a large area of the eyelets to provide a secure attachment of the eyelets to the tape.

Preferably, the feed dog 64 is adjustable 100 to compensate for different spacing of the fastener elements on different pieces of work. As shown, the slide bar 66 is formed in two superposed relatively longitudinally slidable sections 66a and 66b adjustably connected by a slot and screw connection 66c. The pin 105 of the pin and slot connection 72 is carried by the upper section 66b. By loosening the screw 66c, the two sections 66a and 66b may be slid relatively to each other to move the dog with respect to the pin and slot connection 72 so that the dog may be brought into proper cooperative relation to the fastener 110 elements.

While I have shown and described the invention as specifically used for sewing eyelets upon fastener tape, and as embodied in certain details of construction, it should be understood that this is primarily for the purpose of illustrating the principles of the invention and that the machine is susceptible to use for other purposes and may be embodied in many different details of construction without departing from the spirit or scope of the invention.

Having thus described my invention, what 115 I claim is:

1. In a sewing machine for sewing fastener elements on work, a sewing mechanism including a needle, means at the work discharge side of said needle for feeding work 120

- to the needle with a step-by-step motion to form a line of stitches, and auxiliary work advancing means between said needle and said work feeding means including a member to engage the fastener elements which have been stitched and move the work from the needle at a different rate than said work feeding mechanism. 5. In a sewing machine for sewing fastener elements on work, a sewing mechanism including a needle, means at the work discharge side of said needle for feeding work to the needle with a step-by-step motion to form a line of stitches, and auxiliary work advancing means between said needle and said work feeding means including a reciprocable dog to engage the fastener elements upon movement in one direction and slip over the fastener elements upon movement in the opposite direction so as to move the work from said needle at a different rate than said work-feeding mechanism. 2. In a sewing machine for sewing fastener elements on work, a sewing mechanism including a needle, means at the work discharge side of said needle for feeding work to the needle with a step-by-step motion to form a line of stitches, and auxiliary work advancing means between said needle and said work feeding means including a reciprocable and oscillatory needle, means for feeding the work relatively to said needle to form a line of stitches between said fastener elements, automatic means to interrupt the operation of said work feeding means and consequently movement of said work thereby as each fastener element approaches the path of said needle, means for simultaneously reciprocating and oscillating said needle while movement of the work by said work feeding means is arrested to form transverse stitches over portions of said fastener elements, and auxiliary work advancing means at the work discharge side of said needle, including a reciprocable slide, a dog pivoted on said slide to engage the fastener elements upon movement in one direction and ride over said fastener elements upon movement in the other direction, a cam, and an operative connection between said cam and said slide to reciprocate the slide and move the work away from said needle at a different rate than said work feeding mechanism. 3. In a sewing machine for sewing fastener elements on work, sewing mechanism including a reciprocable feed dog to engage each of said fastener elements which have been previously stitched to the work, and means for reciprocating said reciprocable feed dog to engage one of said fastener elements and move the work while said needle is oscillating to form said transverse stitches over another fastener element, so that said transverse stitches are spaced from each other. 4. In a sewing machine for sewing fastener elements on work, sewing mechanism including a reciprocable and oscillatory needle, means for feeding the work relatively to said needle to form a line of stitches between said fastener elements, automatic means to interrupt the operation of said work feeding means and consequently movement of said work thereby as each fastener element approaches the path of said needle, means for simultaneously reciprocating and oscillating said needle while movement of the work by said work feeding means is arrested to form transverse stitches over portions of said fastener elements, and auxiliary work advancing means including a feed dog to engage one of said fastener elements and move the work while said work feeding means is at rest to space said transverse stitches. 6. In a sewing machine for sewing fastener elements on work, a sewing mechanism including a needle, means at the work discharge side of said needle for feeding work to the needle with a step-by-step motion to form a line of stitches, a periodically operated stop device to temporarily engage said fastener elements for controlling presentation thereof to said needle as the work is moved, and auxiliary work advancing means including a member to engage a fastener element which has been stitched and move the work from the needle at a different rate than said work feeding mechanism. 7. In a sewing machine for sewing fastener elements on work, sewing mechanism including a reciprocable and oscillatory needle, means for feeding the work relatively to said needle to form a line of stitches between said fastener elements, automatic means to interrupt the operation of said work feeding means and consequently movement of said work thereby as each fastener element approaches the path of said needle, means for simultaneously reciprocating and oscillating said needle while movement of the work by said work feeding means is arrested to form transverse stitches over portions of said fastener elements, and auxiliary work advancing means at the work discharge side of said needle, including a reciprocable slide, a dog pivoted on said slide to engage the fastener elements upon movement in one direction and ride over said fastener elements upon movement in the other direction, a cam, and an operative connection between said cam and said slide to reciprocate the slide and move the work away from said needle at a different rate than said work feeding mechanism so that said dog successively engages said fastener elements to move the work step-by-step while said needle is oscillating to form said transverse stitches, whereby said transverse stitches are spaced from each other.

8. The combination set forth in claim 1 with the addition of means for adjusting said member to compensate for different spacing of the fastener elements on different pieces of work.
9. The combination set forth in claim 2 with the addition of means for adjusting said reciprocable dog to compensate for different spacing of the fastener elements on different pieces of work.
10. The combination set forth in claim 6 with the addition of means for adjusting said dog on said slide to compensate for different spacing of the fastener elements on different pieces of work.
11. In a sewing machine, sewing mechanism including a reciprocable and oscillatory needle, means for feeding work relatively to said needle to form a line of stitches, automatic means to periodically interrupt the operation of said work feeding means and consequently movement of the work thereby, means for simultaneously reciprocating and oscillating said needle to form transverse stitches while movement of the work by said work feeding means is arrested, auxiliary work advancing means for moving the work to space said transverse stitches, and means for actuating said auxiliary work advancing means step-by-step while said work feeding means is at rest.

LEO ROSEMAN.
